[57] **CLAIM**

The ornamental design for a cable lashing machine, substantially as shown.

DESCRIPTION

FIG. 1 is a side elevational view of a cable lashing machine embodying my new design;

FIG. 2 is a side elevational view thereof viewed from the side opposite from FIG. 1;

FIG. 3 is a top plan view thereof;

FIG. 4 is a bottom plan view thereof;

FIG. 5 is an end view thereof as seen from the left end thereof in FIG. 1; and

FIG. 6 is an end view as seen from the right end thereof in FIG. 1.
